UNITED STATES PATENT OFFICE.

CHARLES R. CARPENTER, OF RACINE, WISCONSIN.

COMBINED MOP HEAD AND WRINGER.

SPECIFICATION forming part of Letters Patent No. 787,890, dated April 25, 1905.

Application filed May 8, 1903. Serial No. 156,276.

To all whom it may concern:

Be it known that I, CHARLES R. CARPENTER, a citizen of the United States, residing at Racine, county of Racine, Wisconsin, have invented certain new and useful Improvements in a Combined Mop Head and Wringer; and I do hereby declare the following to be a full, clear, and exact description of the invention, such as will enable others skilled in the art to 10 which it appertains to make and use the same.

This invention relates to certain improvements in mops, and more particularly to improvements in combined mop heads and wringers; and the objects and nature of my 15 invention will be readily understood by those skilled in the art in the light of the following explanations of the constructions shown in the accompanying drawings merely as examples from among other arrangements within 20 the spirit and scope of my invention.

My invention consists in certain novel features of construction and in combinations and arrangements of parts, as more fully and particularly set forth and specified hereinafter.

Referring to the accompanying drawings, Figure 1 is a perspective view of the mop-head, the mop-cloth not being shown to avoid hiding parts, the deflector and water-shed being shown provided with bristles to form a 25 scrub-brush. Fig. 2 is a top plan view showing the mop-cloth in position. Fig. 3 is a longitudinal sectional view showing the crank-roller and the pressure-roller in end elevation, arrows indicating the direction of movement 30 of the mop-cloth when being wrung, the water forced from the cloth and deflected by the water-shed being indicated, the water-shed being shown without the bristles. Fig. 4 is an edge elevation of the mop-head. Fig. 5 is 35 an edge elevation showing a modified arrangement of bearing sockets or depressions for the journals of the crank-roll and a somewhat different arrangement of the pressure-roll with respect to the crank-roll. Fig. 6 is a 40 detail view showing how the pressure-roll is gripped and held by its spring when the crank-roll and mop-cloth are removed.

In the drawings, *a* is the handle of the 45 mop. This handle is secured in any suitable manner to the mop head or frame, which ex-

tends downwardly therefrom. In the specific example illustrated the mop head or frame is formed with a central upwardly-projecting socket *b* to receive the handle *a* and in which the handle is secured. This socket is shown 55 extending up from the top transverse cross-bar of a U-shaped depending metal frame. This frame is composed of said cross-bar and the depending parallel side bars *c*, formed with the forwardly and horizontally elongated 60 vertical side or guide plates *d*, at their lower edges having the horizontal flanges *e*, resting on and secured to the transverse block or plate *f* by screws or other suitable fastening means. The socket *b*, as shown, is formed with the 65 laterally-extending handholds *g*, one of which is shown extended and slotted to form a catch *h* to hold the crank-handle of the crank-roll in locked position against rotation. In the specific example illustrated I form the frame 70 with its socket and handholds in one piece of metal, usually by casting.

i is the crank or wringer-roll arranged a short distance above and parallel with the plate or block *f* and extending between the 75 lower portions of the side bars of said U-shaped frame, so as to leave a sufficient space between said roll and the top surface of plate or block *f* for the free passage of one ply of the endless thick fabric mop-cloth *j*, which 80 passes over said roll. This roll is formed or provided with outwardly-projecting end pintles or journals *k*, rigid with the roll. *l* is a crank-handle at one end rigidly secured to the outer projecting end of one of the pintles 85 *k*. This handle is provided to rotate the said roll and the endless mop-cloth, and it is arranged outside of the mop head or frame and is normally held by the catch *h* to lock the said roll against rotation. The crank-handle 90 is sufficiently flexible to permit its being sprung into and out of locking engagement with said catch. As it is desirable that the said roll carrying the endless mop-cloth be readily removable from the mop-head, although as at present advised I do not wish to so limit all features of my invention, I provide the said side bars of the frame with bearing sockets or depressions *m*, extending inwardly through the front edges of said side 100

bars and open at their front ends. The depth of each socket or depression m is preferably greater than the diameter of the pintle k , and said bearing-sockets are so formed that the 5 said pintles will rest and turn therein and so that the said roll can be readily dropped into the frame from the front with its pintles entering said depressions and can be readily removed by pulling or forcing the same forwardly from the frame. The bearing sockets or depressions can extend directly inwardly transversely of the side bars of the frame, as shown in Fig. 4, or said sockets or depressions can extend downwardly and inwardly at 10 an angle, about as shown at m' , Fig. 5. With either construction the crank-roll is yieldingly and normally confined in operative position in the mop-head by the upper pressure-roll n . This roll n is arranged above and parallel 15 with the crank-roll and is located between the side bars of the frame. This pressure-roll is formed with the end journals or pintles o arranged within the frame and preferably with their outer ends terminating a short distance 20 from the inner faces of the side bars of the frame. This pressure-roll is maintained in position and forcibly and yieldingly held toward the crank-roll and compressing the mop-cloth between the two rolls by a plate-spring 25 p , arranged longitudinally of the under side of the top cross-bar of the U-shaped frame and at its intermediate portion rigidly secured to the central portion of said cross-bar with the free ends of the spring constantly pressing 30 downwardly against the pintles o of the pressure-roll and forcing said roll with the necessary pressure against the mop-cloth. The free ends of said spring are bent to form the vertical portions q between the ends of the 35 pressure-roller and the inner faces of the side bars of the frame, and the lower edges of these free ends of the spring are notched or recessed to receive the pintles of the pressure-roll. These notches open downwardly, so that 40 the pressure-roll can be removed from the spring ends, if desired, after the crank-roll and mop-cloth have been removed from the mop-head. The ends of the spring are so arranged that when the pressure-roll is in its normal 45 operative position compressing the mop-cloth on the crank-roll the ends q will be pressed upwardly and outwardly from the end faces of the pressure-roll; but when the crank-roll and mop-cloth are removed the pressure-roll is forced downwardly by the spring, thereby 50 causing the ends of the spring to move down and the portions q of the ends of the spring to move toward each other and bear against the end faces of the pressure-roll, thereby 55 gripping or clamping said roll and holding it in the mop-head and against dropping therefrom when the mop-cloth is removed. It will hence be observed that the pressure-roll is, in effect, mounted in and carried by its spring 60 and is maintained in proper position in the 65

mop-head by the spring when the crank-roll and mop-cloth are removed, notwithstanding the fact that the pressure-roll is itself removable. The pressure-roll is so arranged with respect to the crank-roll that the pressure of the spring maintains the pintles of the crank-roll in the open bearing-sockets of the side bars while the mop is in use and while the rolls are being rotated to wring the mop-cloth. 70

In the construction shown in Fig. 5 the axes of the two rolls are approximately in the same plane with the U-shaped frame and the handle, so that the pressure of the spring holds the crank-roll pintles down into the recessed lower portions of the bearing-sockets. In this construction the crank-roll can be removed by reversing the mop and jerking downwardly on the mop-cloth to force the crank-roll downwardly and out of the sockets. 80

In the arrangement shown in other views of the drawings the pressure-roll is shown arranged in a plane slightly in advance of the plane of the frame and axis of the crank-roll, so as to normally hold the crank-roll against outward movement and maintain its pintles at the inner ends of the open sockets m . In this construction the crank-roll and mop-cloth can be removed by forcing the crank-roll directly outwardly, which will cause the pressure-roll to move up against its spring sufficiently to permit the outward passage of the crank-roll from the frame. 85

The side bars of the U-shaped frame preferably extend upwardly and rearwardly from the upper rear corners of and at an angle to the vertical guide-plates d , and said guide-plates extend forwardly transversely across the ends of the block or plate f . The crank-roll is preferably arranged above the longitudinal rear edge portion of the plate or block f , so that the lower ply of the endless mop-cloth passes from the under surface of the crank-roll forwardly and transversely across the upper face of the plate f , between the elongated guides d , and hangs from the front longitudinal edge of said plate f . When the mop-head is held in operative position for wringing the mop-cloth, the upper face of the plate f is preferably inclined slightly downwardly and rearwardly, (see Fig. 3,) so that when the crank-roll is rotated in the direction of the arrow the under ply of the mop-cloth will travel upwardly to the front edge of the plate f and rearwardly across the top face of said plate and upwardly at the rear of the crank-roll and forwardly between the two rolls. The water is squeezed and wrung from the mop-cloth and falls at the rear of the crank-roll onto the plate f and is deflected thereby from the mop-cloth and discharged at the rear edge of the plate f . The plate f thus forms a deflector or water-shed, keeping the water from the mop-cloth and enabling the operator to thoroughly wring the mop-cloth by a few 100

turns of the crank-handle. The deflector or water-shed *f*, arranged approximately as described with respect to the mop-cloth, permits the employment of an endless mop-cloth 5 and permits the efficient wringing of the endless mop-cloth by preventing the water wrung from the cloth from running down the length of the endless cloth. The guide-plates *d* engage the edges of the lower ply of the mop-cloth for a considerable distance in advance 10 of the crank-roll and effectively maintain said cloth in the proper position with respect to the rolls and prevent doubling of the edges of the cloth and the cloth from working edge-wise longitudinally of the rolls. 15

When the mop is in use, the mop-cloth can be forced and held to the floor or other surface with the desired pressure by the plate or block *f*, as the mop-cloth can pass under the 20 bottom face of said plate or under the edge thereof.

The plate or block *f* can be formed by the back or body of a scrub-brush, as shown in Fig. 2, or can be composed of a plain block 25 or plate, as shown in other figures of the drawings, as the brush is not essential to the operation of the device when employed solely as a mop. However, the usefulness of the device is increased by including the scrub-brush, and I prefer to employ the same. 30

The terms "water-shed," "deflector," "plate," and "block" are employed herein in a broad sense in referring to the member *f*, whether or not said member is used in connection with bristles or a scrub-brush. 35

It is evident that various changes might be made in the forms, constructions, and arrangements of the parts described without departing from the spirit and scope of my invention. Hence I do not wish to limit my 40 invention to the constructions shown, but consider myself entitled to all such changes as fall within the spirit and scope of my invention.

Having thus fully described my invention, 45 what I claim as new, and desire to secure by Letters Patent of the United States, is—

1. In a mop, in combination, a mop-head frame comprising side bars, having bearing sockets or depressions opening outwardly 50 through the longitudinal edges thereof, an independently-removable wringer-roll carrying a mop-cloth and provided with an operating-handle and with end pintles removably confined and turning in said depressions, a spring-held pressure-roll coöoperating with and removably holding the wringer-roll with its 55 pintles in said depressions, and pressure-roll-supporting means independent of and disconnected from said wringer-roll.

2. A mop-head provided with removable wringer-rolls, one of said rolls having end pintles, and a plate-spring having its downwardly-pressing free ends extending beside the end faces of said roll and bearing against and 60 notched to receive said pintles, said free ends

tending to spring toward each other and removably grip said roll when the other roll is removed.

3. In combination, a mop-head frame having side bars, a transversely-arranged plate 70 or block secured to the lower ends thereof, a pair of parallel removable rotary wringer-rolls adapted to receive a mop-cloth between them, the side bars of the frame having open end sockets, and the lower roll having pintles 75 removably resting in said sockets, the upper roll having pintles between the side bars, and spring ends secured to the frame with their extremities extending beside the end faces of said upper roll and bearing against the pintles 80 thereof and removably carrying and supporting said roll when the lower roll and cloth are removed.

4. In a mop, in combination, a U-shaped frame having a handle-socket projecting upwardly from the top bar of said frame and provided with the lateral rigid handhold located above said frame top bar and at one end formed with a catch, and rotary spring-held wringer-rolls carried by said frame, one 90 of said rolls having an end crank-handle outside of said frame arranged to spring into locking engagement with said catch. 85

5. In a mop, in combination, a frame comprising downwardly-extending sides at their 95 lower portions having bearing-sockets opening outwardly through the edges of said sides, and horizontally-elongated parallel vertical guide-plates extending forwardly from the lower ends of said sides, a horizontally-disposed deflector-plate rigid with and connecting said guide-plates, said guide-plates extending transversely across the top face of said deflector-plate, a removable rotary crank-roll provided with a hand-crank and having 100 journals removably fitting in said sockets, and a spring-pressed wringer-roll yieldingly held to said crank-roll and holding the same removably in said frame. 105

6. In a mop, in combination, a frame comprising downwardly-extending sides and vertical horizontally-elongated guide-plates having lateral securing-flanges at their lower longitudinal edges, a horizontal transversely-arranged deflector-plate, said guide-plates extending transversely across the ends of said deflector-plate approximately to the front edge thereof with said flanges resting on the top face thereof and rigidly secured thereto, a wringer-roll mounted in said sides above said 115 plate and means coacting with said roll to compress a mop-cloth thereon. 120

7. In combination, a mop-head comprising side bars, a deflector arranged transversely between the side bars and rigid with the lower 125 ends thereof, said side bars extending upwardly and rearwardly from the top face of the deflector and at an angle thereto, said side bars formed with horizontally-elongated vertical guide-plates extending transversely 130

across the top face of the deflector and secured thereto, a removable rotary wringer-roll mounted in said bars and arranged above the top face of said deflector, and means co-operating with said roll to compress a mop-cloth.

8. A mop comprising in combination, a head-frame having downwardly-extending sides formed at their longitudinal edges with the outwardly-opening bearing depressions or sockets, an independently-removable wringer-roll having its journals normally confined to turn in said depressions, said roll adapted to carry an endless mop-cloth removable with said roll, and spring-held means disconnected from said roll and compressing the cloth thereon and yieldingly holding said roll against lateral displacement from said depressions, whereby outward lateral pressure against said roll will laterally displace said means and permit independent removal of said roll with the cloth, thereby permitting endwise removal of the roll from the cloth.

9. In a mop, in combination, a frame having downwardly-extending sides, a transversely-arranged deflector-plate rigid with said sides, said frame sides having bearing-sockets opening outwardly through the longitudinal edges thereof, a removable rotary wringer-roll between said frame sides and having its journals removably confined and turning in said sockets and carrying an endless mop-cloth removable with said roll, and yielding roller-retaining means yieldingly retaining the roll with its journals in said sockets, said plate arranged below said roll and upholding said mop-cloth.

10. A combined mop head and wringer comprising a transverse deflector-plate, a rotary wringer-roll arranged just above said plate, and carrying an endless mop-cloth extending transversely across the top face of said plate, said plate upholding and deflecting said cloth, yielding means compressing the cloth on the roll, and mop-cloth guides extending transversely across the top face of said plate.

11. In a mop, in combination, a mop-head frame, a rotary wringer-roll carried thereby, an endless mop-cloth carried by said roll, means compressing the cloth, and a mop-cloth de-

flector and water-shed rigid with said frame and arranged closely beneath said roll and upholding and deflecting the mop-cloth to one side of the vertical plane of the falling water squeezed from said cloth, said water-shed extending into said plane of the falling water and thereby deflecting said water from the mop-cloth.

12. A mop comprising a mop head or frame having the horizontally-disposed wide watershed or deflector-plate rigid therewith, a removable wringer-roll mounted in said frame close above said plate, an endless mop-cloth passing around and removable with said roll with its under ply arranged transversely across the top face of said plate and depending from the front edge thereof.

13. In a mop, in combination, a transverse wide horizontally-disposed deflector-plate, mop-head-frame sides rigid with and extending upwardly and rearwardly from the end portions of said plate, said plate having mop-cloth guides extending transversely across the end portions of its top face, a removable wringer-roll close above said plate and between and removably mounted in said arms, and mop-cloth-compressing means co-operating with said roll.

14. In a mop, in combination, a mop-head frame having downwardly-extending sides, a rotary wringer-roll mounted in said sides, an endless mop-cloth carried by said roll, means co-operating with said roll to compress said cloth thereon, and a flat wide transverse deflector-plate rigid with the lower ends of said sides and arranged closely below said roll and co-operating with said mop-cloth to uphold and deflect the mop-cloth laterally from the path of the water squeezed from the cloth, said cloth passing transversely across the top face of said deflector and hanging from the front edge thereof.

In testimony whereof I affix my signature in presence of two witnesses.

CHARLES R. CARPENTER.
